UNITED STATES PATENT OFFICE.

NELSON H. FOOKS, OF PRESTON, MARYLAND.

APPARATUS FOR HEAT-TREATING SUBSTANCES PACKED IN SEALED RECEPTACLES.

Original application filed December 5, 1924, Serial No. 754,126. Divided and this application filed April 11, 1925. Serial No. 22,613.

To all whom it may concern:

Be it known that I, NELSON H. FOOKS, a citizen of the United States, residing at Preston, in the county of Caroline and State 5 of Maryland, have invented certain new and useful Improvements in Apparatus for Heat-Treating Substances Packed in Sealed Receptacles; and I do hereby declare the following to be a full, clear, and exact description 10 of the invention, such as will enable others skilled in the art to which it appertains to make and use the same.

This invention has for its object to provide an improved method of heat-treating 15 foods in sealed receptacles, such as tin cans, whereby the cooking period may be easily controlled and the receptacles cooled to reduce the internal pressure therein before being discharged into the atmosphere.

20 In methods where the receptacles are progressed through a retort along a definite path it has been proposed to control the cooking period by ejecting the receptacles from the retort at a selected point or points 25 in their path of travel. This manner of control not only involves the employment of more or less complicated and consequently expensive machinery, but also necessitates the discharge of the receptacles into the atmosphere directly from the heating medium 30 with consequent danger of springing of the seams of the cans and resultant loss of the product, particularly where the high cooking temperatures are employed.

35 According to my invention, the sealed receptacles are progressed along a path of definite length within the retort irrespective of the cooking period and are cooled before discharge from the same. The retort is filled 40 with superposed fluids maintained at different temperatures, the cans being passed from one fluid to the other in their course of travel through the retort. To control the cooking period it is merely necessary to raise 45 the level of the fluid of lower temperature. Inasmuch as the cans are progressed through the retort at a definite rate of movement, it follows that they will remain in the fluid of higher temperature a greater or lesser 50 time depending on the depth of the hotter fluid, which depth is controlled by the level of the cooler fluid. The fluid of lower temperature is preferably water and obviously constitutes the cooling medium; the fluid

of higher temperatures is preferably a 55 gaseous medium, such as steam but may be a heated fixed gas, such as air, or a mixture of steam and air. The apparatus for carrying out my improved process is extremely simple necessitating, outside of the can-carrying mechanism, relatively simple means 60 for maintaining the heating and cooling fluids at proper levels and temperatures.

In the accompanying drawing, Fig. 1 is a 65 part sectional and part diagrammatic elevation of a cooker and cooler in conjunction with which my improved process may be practiced.

Fig. 2 is a bottom plan view of one group 70 of pipes through which the heating medium is entered into the apparatus shown in Fig. 1.

In the drawing Fig. 1 indicates generally a retort or tank provided with a gauge glass tube for indicating the level of the liquid in the retort; 3 a water supply pipe; 4 a pipe 75 or conduit for supplying heating medium to the retort, said pipe having valved lateral extensions 5 each in connection with a group of horizontally disposed pipes generally indicated at 6 and perforated on their bottoms. 80 In filling and maintaining the retort or tank with the heating medium, the latter will be admitted through that group or bank of pipes 6 which is closest to the level of the liquid maintained in the tank, thereby ob- 85 viating any dead or cold space above the cooling liquid.

The desired level of the cooling liquid is maintained by providing a series of steam traps, generally indicated at 7, at different 90 levels, the traps permitting the cooling liquid to flow out therethrough but not steam, as will be readily understood, the waste pipe in connection with said traps being indicated at 8, each trap having a controlling valve 9 95 exterior thereof to permit the liquid level to be raised to the next higher trap, as will be readily understood.

The retort or tank is provided with any suitable form of can-conveying means which 100 will permit the cans to be moved at a uniform rate from one level to another in the tank through the heating and cooling mediums. For simplicity of showing no specific can-moving means is shown but only 105 the path which the cans will follow in their progress through the tank, such path being indicated at 10 by a line of cans. When the

* gaseous medium is maintained under pressure greater than atmospheric pressure the cans may be entered into the retort or tank through a rotary valve 11, and be discharged therefrom by a similar valve 12. However, when the process is practiced without maintaining the gaseous heating medium under pressure, any suitable means for feeding the cans and receiving them from the endless 10 conveyor may be employed. In the present showing of the cooker and cooler the cans after passing through the cooling liquid at the bottom of the tank are shown as passing upwardly through a well 13 formed by a 15 partition 14 and thence outwardly through the discharge valve 12.

It will now be appreciated that in its broadest aspect my invention contemplates the cooking and cooling of substances within 20 sealed receptacles by passing the receptacles through superposed fluids while maintaining the fluids at different temperatures. That when steam is used as the heating medium temperature of the same may be raised 25 by maintaining the steam under pressure greater than atmospheric; that the method of controlling the cooking period is not dependent on maintaining a pressure greater than atmospheric pressure within the tank; 30 and that the invention is just as applicable to a so-called open air cooker and cooler as to a pressure cooker and cooler. When the cooling medium is water and the heating medium is a gaseous substance the receptacles 35 will, of course, be progressed through the tank from the top to the bottom thereof inasmuch as the heating medium will then overlie the water. It may, however, be found desirable to utilize the water as the heating 40 medium and to maintain a suitable cooling medium thereabove for cooling the cans, in which event the cans would obviously be passed from a lower level to a higher level, namely: through the cooking water at the 45 lower level and the cooling medium thereabove. It is also possible to use non-miscible liquids, one of which will serve as

the heating medium and the other the cooling medium.

The desired temperature of the cooling 50 water is kept up by supplying the cooling water through the pipe 3 and the heating medium is maintained by supplying the same through the conduit 4, as will be readily understood. The gauge glass tube affords 55 a ready means for determining the level of the liquid within the tank.

The appended claims are intended to define what I consider to be the various novel 60 features of the invention.

This application is a division of my application Serial 754,126, filed December 5, 1924.

What I claim is:

1. In a device for cooking and controlling 65 the cooking period of substances within sealed receptacles, the combination with a tank, a body of relatively cooling liquid partially filling the tank, a body of relatively hot fluid superposed on the body of cooling liquid, a path for the receptacles extending from the upper to the lower level of the tank, and means for maintaining said bodies at predetermined levels.

2. In a device for cooking and controlling 75 the cooking period of substances within sealed receptacles, the combination with a tank, a body of cooling water partially filling the tank, a body of gaseous heating medium superposed over the water, and a continuous fixed path of different levels along 80 which the receptacles are passed through the heating and cooling mediums.

3. In a device of the character described, 85 the combination of a tank, a continuous path extending from the top to the bottom of the tank, a body of cooling water in the tank, a body of steam overlying the body of water, means including steam traps for maintaining the water at a given level, and means 90 for keeping the tank filled with steam.

In testimony whereof I affix my signature.

NELSON H. FOOKS.
